United States Patent Office

Des. 212,680
Patented Nov. 12, 1968

212,680

PAPERBOARD CARTON

Momofuku Ando, 34-7 Masumicho, Ikeda, Japan

Filed May 16, 1967, Ser. No. 7,143

Term of patent 14 years

(Cl. D9—225)

FIG.6

FIG.3

FIG.1

FIG.4

FIG.5

FIG.2

FIG. 1 is a front elevation of a paperboard carton showing my new design;

FIG. 2 is a rear elevation thereof;

FIG. 3 is an end elevation thereof as seen from the left of FIG. 1;

FIG. 4 is an end elevation thereof as seen from the right of FIG. 1;

FIG. 5 is an elevation thereof as seen from the bottom of FIG. 1; and

FIG. 6 is an elevation thereof as seen from the top of FIG. 1.

I claim:

The ornamental design for a paperboard carton, as shown.
